2,009,494

ELECTROLYTIC CONDENSER

Paul Hetenyi, New York, N. Y., assignor to Solar
Manufacturing Corporation, a corporation of
New York

Application July 19, 1932, Serial No. 623,316

5 Claims. (Cl. 175—315)

It is among the general objects of the present invention to provide an electrical condenser having an improved power factor and large capacity.

Another object of the invention is to provide 5 a condenser of the electrolytic type using a thin aluminum anode foil of disc formation so supported as to have its entire surface in contact with the electrolyte; said disc formation of the anode making it possible to put a large capacity 10 in a comparatively small space.

Another object of the invention is to provide 15 a condenser of the electrolytic type having its anode constructed of aluminum discs which are connected to one another by a narrow link of the same material, and which are supported by an aluminum rod constituting the electrode pole which passes through holes punched in the centers of the discs; the rod being centrally supported in an electrolyte receptacle of chemical- 20 resisting and non-filming metal, which acts as the cathode.

With these and other objects in view, to be 25 more fully set forth hereinafter, the invention consists in the novel construction, combination of elements and arrangement of parts which will be exemplified in the operation and construction herein described in the following specification and illustrated in the accompanying drawing.

The disclosure made the basis of exemplifying 30 the present inventive concept suggests a practical embodiment thereof, but the invention is not to be restricted to the exact details of this disclosure, and the latter therefore is to be understood from an illustrative, rather than a restrictive 35 standpoint.

The invention will first be described in connection with the drawing, wherein similar reference characters are used to designate corresponding parts throughout the several views, and more 40 specifically defined and indicated in the appended claims.

Attention is directed to the drawing, in which— Fig. 1 is an elevational view, partly in section 45 of my condenser, which illustrates how the integral anode discs are supported in position;

Fig. 2 is a sectional view taken on the line 2—2 of Fig. 1 and looking in the direction of the arrows; and

Fig. 3 is a plan view of a portion of the anode 50 disc strip before it is bent to the form illustrated in Figs. 1 and 2, and which illustrates the essence of the invention.

Referring more particularly to the drawing, the 55 form of the invention herein shown by way of illustration includes a suitable electrolyte recep-

tacle 10 which is preferably formed of copper or other suitable chemical-resisting and non-filming metal. Near the upper end of the receptacle is the inwardly turned annular shoulder 11. Between this shoulder and the inwardly turned end 12 of the tube is secured a breather construction to permit the escape of any gases resulting from electrolytic action of the electrolyte. This breather construction is not illustrated in the drawing for it forms no part of the invention. Anyone of the many existing types could be utilized.

Integral with the bottom of the receptacle is the externally threaded boss 13 which is conically bored to receive the insulating bushing 14 which supports the anode electrode pole 15. The end of the electrode that extends from the bottom of the bushing is threaded to receive the nuts 16 which are jammed against the insulating washer 17 to insure a tight seal between the boss 13 and 20 the bushing 14. The downward pull of the nuts also insure a tight seal between the upper end of the bushing and the collar 18 of the electrode.

The anode discs 19 are stamped from a very thin strip of aluminum foil and are integrally 25 connected by the narrow links 20 to form a continuous chain. When the disc strip is bent into the fluted form most clearly illustrated in Fig. 1, the apertures 21, punched in the centers of the discs are brought into alignment in order that 30 the electrode pole 15 may be passed through them and its end riveted over as shown at 15^a in Figs. 1 and 2 to retain it in position. The over-all length of the anode before it is placed in position is slightly greater than that part of the electrode 15 35 which extends above its collar 18, and upon which it is supported. This makes it necessary to compress it to secure it in position, and the tension created by doing so insures against any movement whatsoever.

As Fig. 1 of the drawing clearly shows, the individual disks, forming as a whole a resilient zigzag-bent spring, are, when compressed, still at inclined positions in relation to each other as well as toward a horizontal plane, going through the 45 vertical axis. This is important, as thereby the air bubbles, formed through electrolytic action, can escape along the various disks toward the edges and are not entrapped.

It is readily seen that by constructing electrolytic condenser anodes of this chain disc type, condensers of any required capacity can be easily and inexpensively constructed.

The condenser is adapted to be mounted in a suitable mounting 22 as illustrated in Fig. 1, by 55

means of the externally threaded boss 13 passing through an aperture and being engaged by the nut 23.

In accordance with the provisions of the patent statute, I have described my invention, but I desire it understood that it is not confined to the particular form shown and described, the same being merely illustrative, and that the invention can be carried out in other ways without departing from the spirit of my invention, and therefore, I claim broadly the right to employ all equivalent instrumentalities coming within the scope of the appended claims, and by means of which, objects of my invention are attained and new results accomplished, as it is obvious that the particular embodiments herein shown and described are only some of many that can be employed to attain these objects and accomplish these results.

Having now described my invention, what I claim and desire to secure by Letters Patent, is:

1. In an electrolytic condenser the combination with a cathode container of a plurality of flat anode discs, superimposed in such fashion that they are alternately inclined toward each other at opposite angles to facilitate the disengagement of air bubbles, due to electrolytic action.

2. An electrolytic upright condenser having a plurality of apertured flat anode plates, made of one continuous ribbon, bent and rebent alternately in such fashion that it forms a zigzag ascent of superimposed single plates, inclined toward each other and toward the vertical axis of the condenser, and an electrode pole, passing through the apertures of said plates and provided with means to secure the plates in proper position.

3. In an electrolytic condenser, in combination with a cathode container and an electrolyte therein, an anode comprising a pole supported in an

upright position and centrally located relative to the container and a continuous strip of thin metal perforated at spaced intervals, said strip being bent in a sinuous curve and said pole being inserted through said perforations to support the strip and means at the upper end of said pole to keep said strip under tension and below the level of the electrolyte.

4. In an electrolytic condenser in combination with a cathode container and an electrolyte therein, an anode comprising a pole supported in an upright position and centrally located relative to the container and a continuous strip of thin metal comprising disc portions and narrow connecting portions and having perforations centrally located in said disc portions, said strip being bent in a sinuous curve and said pole being inserted through said perforations to support said strip, and means at the upper end of said pole to keep said strip under tension and below the level of the electrolyte.

5. In an electrolytic condenser, in combination with a cathode container and an electrolyte therein, an anode comprising a pole supported in an upright position and centrally located relative to the container and a continuous strip of thin metal comprising disc portions and narrow connecting portions and having perforations centrally located in said disc portions, said strip being bent in a sinuous curve and said pole being inserted through said perforations to support said strip with said disc portions transverse and said connecting portions parallel to the wall of the container, and means at the upper end of said pole to keep said strip under tension and below the level of the electrolyte.

PAUL HETENYI.
